(57) **CLAIM**

The ornamental design for the tire step assembly, as shown and described.

DESCRIPTION

FIG. 1 is a front elevational view of the tire step assembly showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of thereof taken from above and to the left;

FIG. 8 is a perspective view of thereof taken from above and to the left showing the tire step assembly in a folded storage condition;

FIG. 9 is a front elevational view of a second embodiment of the tire step assembly showing my new design;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of thereof taken from above and to the left; and,

FIG. 16 is a perspective view of thereof taken from above and to the left showing the second embodiment of the tire step assembly in a folded storage condition.

The representation of the tire shown in broken lines in FIGS. 7 and 15 illustrates the use environment of the tire step assembly and forms no part of the present invention.
